ATTACHMENT FOR PHOTOCOPY MACHINES

Edward R. Sabel, Rochester, N. Y., assignor to
The Haloid Company, Rochester, N. Y., a corporation of New York

Application September 10, 1938, Serial No. 229,232

5 Claims. (Cl. 88—24)

This invention relates to an attachment for photocopy machines, of the general type that utilizes a continuous strip of photocopy paper, a portion of which is fed through and cut off after exposure, and it has for its object to afford a mechanism that can be readily applied to any conventional photocopy machine and is operable to permit making copies or enlargements from any selected portion of a miniature continuous film.

The invention has for a further purpose to afford a structure that is particularly applicable to the enlarging of portions of continuous film such as used for photographing checks in banks and for making other records where it is desirable to select a particular part of such film for enlarging.

An additional purpose of the invention is to afford a mechanism attachable to a photocopy machine preferably as a unit, and which includes film supporting and winding means by which any part of a film can be selected for reproduction, and which is positionable to project the image of the selected portion into the projection opening of the photocopy machine on to the light sensitive copy paper, and is also movable to a position which projects the image downwardly on to a copy board or screen, thereby enabling the operator readily to select and bring any desired portion of the film to the proper position for making the required copy.

Another object of the invention is to provide a construction that is simple and practical, which is efficient for the purposes in view, easy to operate, and which can be manufactured at a reasonable cost.

To these and other ends, the invention consists in the construction and arrangement of parts that will appear clearly from the following description when read in conjunction with the accompanying drawings, the novel features being pointed out in the claims following the specification.

In the drawings:

Fig. 1 is a side elevation showing the application of a preferred embodiment of the invention to a conventional type of photocopy machine;

Fig. 2 is a side elevation looking in the opposite direction;

Fig. 3 is a side elevation looking in the same direction as Fig. 1, with the carrier frame swung upwardly for projecting the image downwardly on to the copy board or screen;

Fig. 4 is a front elevation with the lamp hous-

ing swung outwardly to permit access to the film and film track, and

Fig. 5 is a horizontal sectional view taken centrally of the lamp housing in Fig. 1.

Referring more particularly to the drawings in which like reference numerals refer to the same parts throughout the several views, the invention is illustrated in one practical embodiment in the form of a unitary assembly that includes a supporting member consisting of a block 10 that is suitably fastened to the front plate 2 of the photocopy machine, while 3 designate oppositely arranged bars that are pivotally mounted on the block 1 and form part of a carrier frame upon which the parts now to be described are all mounted, and which can be swung out of the way when not in use to permit operating the photocopy machine in the usual way.

The carrier frame includes a central portion 4 having a suitable projection opening therein 20 over which the film 6 is adapted to be adjustably positioned, the film being mounted on and wound between the spools 7 and 8, which are supported respectively on arms 9 and 10. In order to enable the operator to adjust the film readily to any desired position, it travels between two feed rollers 11 and 12, one of which is mounted on a shaft 13 that carries an operating handle 14 at one end and a pulley 15 at its opposite end, while 16 is a belt connecting said pulley 15 with a pulley 17 mounted on the shaft which carries the lower spool 8.

The image is projected by means of light from a lamp in the lamp housing 21 which is pivoted to the carrier frame so as to swing laterally to permit inserting the film, the lamp housing being held in operative position by a spring catch 22 which engages the plate 23 at the forward part of the lamp housing and retains it against the central portion 4 of the carrier frame, it being understood that the film travels in a track that is provided between the plate 23 on the lamp housing and the central part 4 of the carrier frame.

The lamp housing 21 is provided with a suitable condensing lens located between the lamp and the film, while on the opposite side of the film is provided a suitable projecting lens located in a lens barrel 24, the latter being positionable when in operation in the projection opening of the front plate of the photocopy machine.

When using the device, the usual lens and prism assembly is removed from the projection opening in the photo-copy machine, and the pro-

jecting lens in the lens barrel 24 being located in said opening, projects an image from the selected part of the film on to the light sensitive paper.

- 5 It is essential to provide means enabling the operator to select any particular part of the film to be copied, and this is accomplished by swinging the carrier frame upwardly to the position shown in Fig. 3, it being held in such position by a spring catch 26 engaging one of the bars 8. When in this position, the image can be projected downwardly on to the copy board of the machine or to a suitable screen, and the operator may, by turning handle 14, wind the film 10 until the particular part that is to be copied is located. The carrier frame is then swung downwardly to the operative position shown in Fig. 1, where it is ready to project on to the sensitized paper when the exposure is made.
- 15 20 It will be understood that the lamp housing is normally maintained in closed position as shown in Fig. 1, and is swung to its open position only for the purpose of threading a film into the machine, or permitting access to the film or film track.

25 While the invention has been described in connection with the particular construction shown, it is not confined to this precise arrangement, and the application is intended to cover any 30 modifications or departures that may come within the purposes of the improvement or the scope of the following claims.

I claim:

- 35 1. The combination with a photocopy machine including a front plate having a projection opening therein, of a supporting member attachable to the front plate above said projection opening, a carrier frame pivotally secured to said supporting member, said carrier frame including upwardly and downwardly extending 40 arms, film supporting spools mounted on said arms, film winding means on the carrier frame, a lamp housing pivotally mounted on the carrier frame on one side of the film, a condensing lens in said lamp housing, a projecting lens and lens barrel 45 on the other side of said film, said lens barrel being positionable in the projection opening in said front plate, and the carrier frame being shiftable on said supporting member to an upward position for projecting an image from 50 the film downwardly.

55 2. In a photocopy machine, the combination with a vertically disposed front plate having an opening adapted to receive a projecting lens, a carrier frame pivotally mounted on said front plate at a point above said opening, a housing on said carrier frame, a lamp and condensing

lens in said housing, a projecting lens and lens barrel mounted on said carrier frame, said projecting lens being positionable in said opening of the front plate for projecting an image into the photocopy machine, and means for supporting and feeding a film on the carrier frame between said housing and said lens barrel, the carrier frame being tiltable about a point above said opening in the front plate and operable to support said lens barrel in said opening or to support the lens barrel in a vertical position so as to project an image downwardly on to a horizontal screen.

3. In a photocopy machine, the combination with a vertically disposed front plate having an 15 opening therein adapted to receive a projecting lens, a carrier frame pivotally attached to said front plate at a point above said opening, a projecting lens and lens barrel mounted on said carrier frame, film supporting means on the 20 carrier frame, and a lamp housing mounted on the carrier frame, said carrier frame being movable to position the lens barrel in said opening of the front plate so as to project an image into the photocopy machine or to an upright position to project an image vertically downwardly 25 on to a horizontal screen.

4. In a photocopy machine, the combination with a vertically disposed front plate having an opening adapted to receive a projecting lens, a 30 carrier frame pivotally mounted on said front plate at a point above said opening, film supporting means mounted on the carrier frame, a housing located on the carrier frame on one side of the film, a lamp and condensing lens in 35 said housing, and a projecting lens and lens barrel located on said carrier frame on the other side of the film, said lens barrel being positionable in said opening in the front plate to project an image into the photocopy machine or movable to a vertical position to project an image 40 downwardly on to a horizontal screen.

5. In a photocopy machine, the combination with a vertically disposed front plate having an opening adapted to receive a projecting lens, a 45 carrier frame pivotally attached to said front plate at a point above said opening, film supporting and winding means on the carrier frame, a lamp housing pivotally mounted on the carrier frame on one side of the film, and a projecting 50 lens and lens barrel on the carrier frame on the other side of said film, said lens barrel being positionable in said opening in the front plate to project an image into the photocopy machine or positionable vertically to project an image 55 downwardly on to a horizontal screen.

EDWARD R. SABEL.
